DANCING TAP

Frank J. Du Mont and Dorothy H. Sargent, Philadelphia, Pa., assignors to Du Mont, Sargent and Casper, a partnership composed of Frank J. Du Mont, Dorothy H. Sargent, and Joseph E. Casper

Application June 21, 1946; Serial No. 678,494

7 Claims. (Cl. 36—8.3)

1

This invention relates to taps for dancing shoes, and in particular, to an improved tap wherein the elements thereof may be loosely held to the toe or heel of the shoe without danger of the screws or other mounting means working out, or of the taps working loose, or coming off, and thereby causing embarrassment to the dancer.

Various types of taps have been applied to dancing shoes which are normally held by screws, and to increase or improve sound effects, the position of the screws is adjusted by the dancer before the dance is started, and by accurate adjustment, the exact sound desired may be obtained by loosening or tightening the screws. This adjustment of the tap elements or positions of the screws holding the elements to the shoe is referred to as "tuning the taps."

To further increase or improve sound effects in taps of dancing shoes, jingling elements, such as flat metal washers, have been incorporated in open spaces in tap elements, and in some instances, the jingling element has been provided with a stem protruding through an opening in the tap for engagement with the floor or surface upon which the dancer is performing.

To further increase sound in tap dancing, other taps have been made with loose circular buttons which engage the surface of the floor, and these are held by surrounding flanges or sockets that are secured to the sole of the shoe.

Substantially all tap elements of this type are secured to the sole or heel of the shoe by screws as it is desired to adjust the position of the screws to tune the taps to different types of dances, and the heads of the screws are open so that they are free to continue to work out of the soles. With the taps mounted in this manner, substantially all dancers have been embarrassed at some time by losing the taps or at least by all of the screws except one working out, wherein the dance is interrupted.

To provide an absolute guarantee against losing the screws or tap elements of tap dancing shoes, the device of this invention contemplates covering the heads of the screws by a freely mounted disc or flat plate which provides the sound element, and then provides a retaining element which prevents loss of the sound element and which may be tightly or positively secured by screws.

The purpose of this invention is, therefore, to provide improved tap elements for dancing shoes, which include loose sound elements, in which mounting screws of the element may also be loose

2

without danger of either the sound element or screws working out.

To obtain sound effects by loosening screws in metal plates attached to soles and heels of dancing shoes obviously has many disadvantages. The dancer is always confronted with the uncomfortable feeling that one screw at least may work out a sufficient distance to scratch or mar the floor or even trip the dancer, causing bodily injury, when executing certain sliding movements.

In loosening the screws with the common solid type of tap, the resulting sound effect is only that caused by the aluminum or other metal tap element contacting the leather of the sole of the shoe. Furthermore, a loose metal element in a metal casing produces a bell tone sound rather than a tap sound.

The object of this invention is, therefore, to provide a tap for dancing shoes having a loose tapping element which produces a metal to metal sound rather than a jingling or bell tone sound, in which the screws holding the tap to the shoe may be tight or loose and positively prevented from working out.

Another object is to provide a loosely held tap element for dancing shoes that is freely held in such a manner that it is movable from side to side, and at the same time, up and down, which gives the dancer an ease of dancing that is not possible with taps of other types or designs.

Another object is to provide a movable element which forms substantially the entire surface of a tap for dancing shoes so that perfect balance may be maintained.

Another object is to provide a movable element in taps for dancing shoes which is slid able in all directions, wherein the dancer is free to move his feet at whatever angle he may desire.

Another object is to provide taps for dancing shoes having movable tapping elements that may be made in various sizes without interfering with the various functions thereof.

Another object is to provide taps for dancing shoes which include substantially large movable disc or sound elements which may be streamlined to improve, rather than destroy, the attractive appearance of the shoes.

Another object is to provide taps for dancing shoes having movable tap elements in which all of the individual parts may readily be replaced without the necessity of purchasing an entire new unit.

Another object is to provide taps for dancing shoes that may readily be fastened to a shoe, slipper, or the like.

Another object is to provide taps for dancing shoes that may be made of aluminum or magnesium alloy, in which the critical parts have sufficient strength to guarantee against breaking, without being objectionably bulky.

Another object is to provide taps for dancing shoes having movable sound elements in which the tap unit may contain several discs or sound elements with various types of openings therein, or solid elements, wherein the sound element may be interchanged for producing different sound effects.

Another object is to provide taps for dancing shoes and the like in which movable sound elements may be included without increasing the size unnecessarily or without forming objectionable, bulky elements that destroy comfort in walking, and also in which the thickness of the tap at the toe and also at the rear of the heel may be increased to provide perfect walking ease with the taps on the shoes. Taps of this design do not make the dancing shoes feel bulky or the dancer uneasy because of improper balance.

Another object is to provide taps for dancing shoes in which the tap at the heel may be set to provide perfect balance with the tap at the toe.

A further object of the invention is to provide taps for dancing shoes having discs forming sound elements which substantially cover the surface of the tap, and in which the disc is not directly held by screws or the like but forms a floating member held in position by an auxiliary locking element.

With these and other objects in view, the invention includes a base element having an overhanging side flange and a flat plate or disc with an extending flange that is freely held under the flange of the base. The base is provided with screw openings positioned under the disc, and the device is provided with a locking element that may be attached either to the sole or base for holding the disc in the base.

For a full and more complete understanding of the invention, reference may be had to the following description and accompanying drawings wherein:

Figure 1 is a view illustrating the tap in position on the toe of a shoe.

Figure 2 illustrates the device attached to the heel of the shoe.

Figure 3 illustrates the base, disc, and locking element with the parts partly separated.

Figure 4 is a typical cross section through the tap.

Figure 5 is a view showing the open end of the tap with part broken away, showing the locking element secured to the base by machine screws.

Figure 6 is a plan view of the tap with part of the flange of the base broken away at one side.

Figure 7 is a similar view illustrating the use of separate locking element at the corners of the base and showing sound openings in the disc.

Figure 8 is a view showing the base with a modification which includes a sound recess in the surface thereof.

Figure 9 is a similar view showing sound openings through the base.

Figure 10 is also a similar view showing a groove in the base for causing different sound effects.

Figure 11 is a section similar to that shown in Figure 4 except that the screws attaching the

base to the sole of the shoe are unscrewed slightly, wherein both the base and sound element are loosely held.

Referring now to the drawings wherein like reference characters denote corresponding parts, the tap of this invention is formed with a base 10, a sound element or disc 11, and a locking member 12.

The base 10 is formed with a base plate 13, shaped to correspond with the surface of the sole of a shoe, and this formed with extending flanges 14 and 15 at the sides with a continuous groove 16 under the flanges. The base plate 13 is provided with screw openings 17 by which the base may be held to the sole of the shoe by flat-head screws 18, as shown in Figure 4, or any suitable holding means. With the screws positioned in the base plate, in the area within the side flanges, the screw heads are covered by the disc 11 so that it is impossible for the screws to work out with the disc in place.

The disc 11 is formed with a flange 19 that slides into the groove 16 from the open end of the base, and when this is in place, the element 12 is secured to the sole by screws 20, as shown in Figure 6, so that the disc 11 can not be removed from the base without removing the locking element 12. The base 10 and also the member 12 may, therefore, be rigidly held to the sole or heel of the shoe, and the screws in both parts may be tight, whereas at the same time, the member 11 may be loose to produce sound effects when tapped. To adjust the parts to tune the device, the element 12 may be removed and the disc 11 slid out so that the screws are accessible, and the screws may be slightly loosened or adjusted to either hold the base tight or loose, wherein the base may co-operate with the element 11 to vary the tone qualities of the sound produced in tapping.

Figure 11 illustrates the positions of the respective parts with the screws 18 unscrewed slightly so that the base 10 is loosely held.

In the design shown in Figure 5, a locking bar 21 is shown, similar to the bar 12, and this is secured to the end of a base 22, similar to the base 10, by screws 23. The screws, being screwed into metal, may, therefore, have comparatively fine threads which facilitate holding with less danger of the screws working loose or coming out.

In the design shown in Figure 7, individual locking elements 24 and 25 are provided at the corners of the base, and these are held by screws 26 similar to the screws 23, thereby providing means for locking the disc at each corner. It will be understood, therefore, that any suitable means may be provided for locking the floating or sound element in the base, and the locking means may either be attached to the base or to the sole or heel of the shoe.

In the design shown in Figure 7, a disc 27, similar to the disc 11, is provided with openings 28 which, in co-operation with the movement of the disc and base, cause a resounding sound effect, and this may be varied by the size and position of the openings. In the base 29 illustrated in Figure 9, similar openings 30 are also provided in the base plate, and it will be understood that both the disc and base may be formed with openings of this type, or the openings may be either in the disc or base.

In the design shown in Figure 8, the base 31 is provided with a central depression or recess 32, and in the design shown in Figure 10, the base 33

is provided with a groove 34, either of which produces different resounding sound effects.

It will be understood, therefore, that the contacting surfaces of the base and sound element or disc 11 may be smooth or formed with openings or depressions, and a plurality of each of these elements may be provided in a unit with the different elements having openings and grooves to produce different sound effects, wherein the elements may be interchanged and combined for different dancers or dances.

While a preferred specific embodiment of the invention is hereinbefore set forth, it is to be clearly understood that the invention is not to be limited to the exact construction illustrated and described because various modifications of the details may be provided in putting the invention into practice within the purview of the appended claims.

What is claimed is:

1. A sound tap for dancing shoes and the like comprising, in combination, a metallic base element having a groove therein, a metallic floating element adapted to be freely positioned in the groove of the base, and a locking element for holding the floating element in the base, said device characterized in that the floating element is positioned to cover means whereby the base may be fastened to the shoe.

2. In a tap for dancing shoes, a horseshoe-like base plate having mounting screw openings therethrough and a downwardly extending web around the outer arcuate edge with a relatively narrow inwardly extending flange integral with the web parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the outer surface of said inwardly extending flange, said floating element carrying a projecting flange around the arcuate outer edge extending into the groove of the base plate limiting outward movement of said floating element, and means retaining said floating element in position upon said base plate.

3. In a tap for dancing shoes, a horseshoe-like base plate having mounting screw openings therethrough and a downwardly extending web around the outer arcuate edge with a relatively narrow inwardly extending flange integral with the web parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the outer surface of said inwardly extending flange, said floating element carrying a projecting flange around the arcuate outer edge extending into the groove of the base plate limiting outward movement of said floating element, and means at the open end of the groove of said horseshoe-like base plate for retaining said floating element in position upon said base plate.

4. In a tap for dancing shoes, a horseshoe-like base plate having mounting screw openings therethrough and a downwardly extending web around the outer arcuate edge with a relatively narrow inwardly extending flange integral with the web

parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the outer surface of said inwardly extending flange, said floating element carrying a projecting flange around the arcuate outer edge extending into the groove of the base plate limiting outward movement of said floating element, and means retaining said floating element in position upon said base plate, the lower surface of said base plate tapering to a comparatively thin edge at the open end thereof.

5. In a tap for dancing shoes, a horseshoe-like base plate having mounting screw openings therethrough and a downwardly extending web around

20 the outer arcuate edge with a relatively narrow inwardly extending flange integral with the web parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the outer surface of said inwardly extending flange, said floating element carrying a projecting flange around the arcuate outer edge extending into the groove of the base plate limiting outward movement of said floating element, and means retaining said floating element in position upon said base plate, the lower surface of said base plate against which the floating element is positioned having recesses therein.

40 6. In a tap for dancing shoes, a horseshoe-like base plate having mounting screw openings therethrough and a downwardly extending web around the outer arcuate edge with a relatively narrow inwardly extending flange integral with the web parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the outer surface of said inwardly extending flange, said floating element carrying a projecting flange around the arcuate outer edge extending into the groove of the base plate limiting outward movement of said floating element, and means retaining said floating element in position upon said base plate, the intermediate portion of said base

50 plate having openings therethrough wherein the said openings are covered by the said floating element.

7. In a tap for dancing shoes, a horseshoe-like base plate having mounting screw openings therethrough and a downwardly extending web around the outer arcuate edge with a relatively narrow inwardly extending flange integral with the web parallel to and spaced from the said base plate providing an inner groove around the arcuate edge of the base plate, a vertically slidable floating element positioned against the said base plate covering the said screw openings and with the outer edge thereof registering with the inner edge of said inwardly extending flange and with the outer surface thereof substantially flush with the

outer surface of said inwardly extending flange, said floating element carrying a projecting flange around the arcuate outer edge extending into the groove of the base plate limiting outward movement of said floating element, a bar positioned against the flat end of the horseshoe-like base plate, and screws extending through the bar into the webs securing the bar in position and retaining the floating element in the base plate.
